(No Model.)

F. J. GEISSINGER.
CORNICE.

No. 271,058.

Patented Jan. 23, 1883.

Inventor
Freeman J. Geissinger
By his atty.

UNITED STATES PATENT OFFICE.

FREEMAN J. GEISSINGER, OF PHILADELPHIA, PENNSYLVANIA.

CORNICE.

SPECIFICATION forming part of Letters Patent No. 271,058, dated January 23, 1883.

Application filed August 18, 1882. (No model.)

To all whom it may concern:

Be it known that I, FREEMAN J. GEISSINGER, of the city and county of Philadelphia, and State of Pennsylvania, have invented an improvement in Roofs.

My invention has reference to roofs and their cornices; and it consists in constructing the cornice-brackets in the form of chimneys or ventilators which extend above the roof and are in communication with the loft, and in many details of construction, all of which are fully set forth in the following specification and shown in the accompanying drawings, which form part thereof.

15 Ventilators have been arranged on the pinnacle of the roof or ridge, with openings into the loft; but they in no wise formed part of the cornice work, and have never been arranged so as to ventilate flat roofs and those in which 20 fire-walls are used, as in the case of a row of buildings.

The object of my invention is to provide suitable means to create a constant circulation of fresh air through the loft, whereby the 25 said loft may be kept cool, and thereby prevent undue heating of the rooms of the house immediately below said loft, rendering them comfortably habitable even in the warmest weather.

30 This invention is particularly adapted to cheaply-built dwellings containing rooms of small size and low ceilings. It is, however, equally adapted to all kinds of buildings, whether residences or not.

35 In the drawings, Figure 1 is a front view, part in elevation and part in section, of my improved roof and cornice, the section being taken on line $z z$ of Fig. 2. Fig. 2 is a sectional elevation of same on line $x x$ of Fig. 1. Fig. 3 40 is a sectional plan of same on line $y y$ of Fig. 1, and Fig. 4 is a sectional elevation of part of the ventilator cornice-bracket in which the top is closed by a screen.

A is the front wall of the building, and A' 45 is the rear wall. B is the division or fire wall, and is located between any two buildings.

E is the roof, and may be constructed in any desired manner, though what is known as the "flat" roof, as shown, in which one end is 50 shown as higher than the other, is preferable.

F is the ceiling, and I the room or compartment. The loft-space J communicates at its

lowest end with the atmosphere by apertures K, below the eaves, or any other equivalent device.

55 C is the cornice, and is preferably made of sheet-iron, and may be secured firmly to the roof E in the usual manner.

D are the cornice-brackets, and are secured to the cornice C and over the upper part of the 60 fire-walls B, but are about four inches wider than the said fire-walls, so as to leave apertures d to connect the loft-space J with the interior of the brackets D, which are made to act as ventilators. The tops of said brackets are 65 provided with exit-apertures G or g, or both, or apertures made in any other convenient shape or form; or the entire top may be left open or covered with a screen, as shown at G' in Fig. 4; but it is preferable to place a covering, H, over the tops of said brackets to protect the vent-apertures and prevent the passage of rain into the said bracket.

If desired, an auxiliary circulation of fresh air may be constantly kept up through the 75 bracket by providing the same with a tube, M, at the bottom, or a simple aperture, L, this latter construction being useful to allow the escape of moisture formed by the condensation of vapor in the atmosphere or when the top of 80 the bracket is left open. If desired, the cornice may open directly into the brackets.

It is evident that the details of construction might be greatly modified without departing from my invention.

85 The operation is as follows: As the air in the loft J becomes heated it tends to escape through the apertures d into the brackets D and out at the top, fresh air passing into the loft by apertures K. The brackets being made 90 of light sheet-iron, they become heated and increase the circulation of the air. As the heated air escapes fresh cool air is admitted, thereby preventing any undue heating of the ceiling F. 95 The arrows indicate the direction of the air-currents.

Now, while my invention is particularly adapted to flat roofs and fire-walls, it is nevertheless adapted to single buildings, and may 100 be placed on the ends or intermediate thereof, or may be placed upon the upper edge of French roofs.

I do not limit myself to any kind of bracket,

as they are varied with almost every new building; but said bracket must be made to act as a ventilator to be comprehended by my invention.

Having now described my invention, what I claim as new, and desire to secure by Letters Patent, is—

1. In a roof for a building, the combination, with the loft, of a cornice, the fire-walls, and 10 ventilating-brackets supported by the cornice, the loft communicating with the brackets to allow a free passage of heated air from the said loft up through said ventilating-brackets, substantially as specified.
- 15 2. A cornice-bracket made hollow to form a ventilator, and provided with apertures at the top, in combination with a cornice, a roof-loft, and air-passages connecting the said loft with the interior of said brackets, substantially as and for the purpose specified.
- 20 3. A cornice-bracket made hollow and provided with openings on the top to form a ventilator, in combination with the cornice, the roof, a ceiling, a loft formed by said roof and 25 ceiling, apertures to admit fresh air to said loft, and air-passages connecting the said loft with the interior of said ventilating-brackets, substantially as and for the purpose specified.
- 25 4. The fire-wall, in combination with a cor-

nice-bracket made of sheet-metal, and provided with vent-apertures at the top, the said cornice-bracket being made hollow and wider than the fire-wall to form air-passages between said wall and sides of the bracket, substantially as shown.

35

5. The combination of the loft J, cornice C, ventilator-bracket D, having apertures at both top and bottom, flues K and d, substantially as and for the purpose specified.

6. The cornice C, ventilating-bracket D, 40 having apertures at the top, fire-wall B, flues or air-passages d, and a loft communicating with said passages, substantially as and for the purpose specified.

7. The combination of ventilating-bracket 45 D, having apertures G at the top, cover or top cap H, fire-wall B, loft J, cornice C, and passages d, substantially as set forth.

8. The combination of ventilating-bracket D, having apertures at top and a tube, M, at 50 bottom, fire-wall B, loft J, cornice C, and passage-ways d, substantially as set forth.

In testimony of which invention I hereunto set my hand.

FREEMAN J. GEISSINGER.
